UNITED STATES PATENT OFFICE.

RUDOLF LOEB, OF JENKINTOWN, PENNSYLVANIA.

THREAD-INSERTING MECHANISM.

Application filed January 19, 1922. Serial No. 530,246.

My invention relates to that type of thread-inserting mechanism wherein the material receiving the thread may be bunched upon a needle carrying such thread; such needle being of considerable length and adapted to receive in bunched condition a considerable amount of material. The thread employed may serve the function of securing together the lapped ends of independent sections of material, or such thread, or a plurality of threads may provide a form of ornamentation upon a fabric, without reference to the joining of independent sections of material.

One object of my invention is to materially facilitate the operation of inserting the thread, whether employed for its ornamental character or for joining a plurality of sections of fabric or other material.

A further object of my invention is to provide a plurality of needles, each carrying a thread whereby I can produce a plurality of rows of stitches providing or simulating a type of embroidery stitches.

A further object of my invention is to provide means whereby the material can be crimped or creased to permit entrance of the needle as the fabric is presented thereto, and a still further object of my invention is to provide means whereby the bunching of such material through which the needle has been passed can be facilitated; the material piling up on the needle carrying such thread.

Other features of my invention will be pointed out hereinafter and referred to in the claims, and mechanism exemplifying my invention and the manner of operating the same is sufficiently disclosed in the accompanying drawings, in which:

Figure 1, is a perspective view, illustrating the device forming the subject of my invention as it may be employed in practice; the same being mounted upon, adjacent to, or in proper relation with respect to a suitable table or other support upon which the fabric or sections of fabric to be embroidered or connected may be conveniently handled.

Fig. 2, is a sectional elevation of threading mechanism within the scope of my invention.

Fig. 3, is a plan view, partly in section, of a portion of the structure forming the subject of my invention.

Fig. 4, is a plan view similar to Fig. 3, illustrating a modified arrangement within the scope of my invention, and

Figs. 5, 6, 7 and 8, are diagrammatic views illustrating fabric to which connecting or ornamental stitches have been applied by the use of my thread-inserting mechanism.

In the drawings, 1 represents a suitable bracket or support, which may be attached by bolts 2, at any convenient point to a suitable frame, preferably of such a character as to hold such bracket or support in a rigid condition. Hinged at 3, to this bracket support by a pivot pin 4, is a movable plate 5, disposed above the same and longitudinally thereof. Carried by the pivot pin 4 of the hinged connection is a block 6, to which an elongated needle 7, is connected; such needle having an eye 8, adjacent its point, adapted to receive a thread 9, from a suitable supply, which thread may pass through an aperture 10, in the block 6, and normally lie alongside the needle.

Carried by the bracket support 1, and the plate 5, disposed above the same, are toothed members 11 and 12, which may be in the form of broad-faced spur wheels and are in effect goffering wheels; such toothed members meshing with each other so that power applied to one will effect movement of the other. While it is possible that the power applying means may be connected to either one of these so called goffering wheels, in the present instance I have shown it as applied to the upper member or wheel 11, and in the present instance a hand-crank 13, is shown as the power applying means. It will be understood, of course that power from a motor or a driven pulley may be employed to actuate these goffering wheels.

As these toothed elements mesh, it will be understood that power applied to one will effect movement of the other and the combined action is such that any fabric, whether single ply, to which ornamental stitches are to be applied, or lapping portions which are to be connected together, will be crimped or goffered by the meshing teeth; thereby making temporary folds at more or less regular intervals, so that as such folds are successively presented to the point of the needle 7, the latter will enter the material and carry the thread through such folds. Continued movement of the toothed members for the

purpose of successively crimping the fabric for its full extent will cause the latter to pile up on the needle.

To facilitate movement of the cloth in piling up on the needle, I preferably provide an endless, toothed chain 15, arranged to pass over the toothed member 11, and over a sheave or idler 16, which is suitably flanged to guide such chain; the toothed elements being annularly notched or grooved at 17 and 18, respectively, to permit passage of the chain and its teeth. When a single needle is employed, it may be disposed centrally with respect to the toothed elements, and the said teeth will be additionally notched or cut away at 19 and 20, respectively to accommodate said needle. If more than one needle is provided, as indicated in Fig. 4, the teeth will be cut away or notched accordingly, to accommodate the same. I preferably apply a cover 21, to enclose the mechanism carried by the upper plate 5.

It will be understood, of course, that the thread applied may be one of a fibrous nature, cotton, linen, wool, silk, or the like, and when ornamental stitches are being applied, yarn of an ornamental character and relatively thick may be applied. If necessary or desirable for any purpose, a wire, or a thread made up of wire filaments, can be carried by the needle to be passed either through fabric, or through any similar or suitable material designed to be connected together or to be ornamented by the thread applied.

In Fig. 5, I have shown the manner in which two sections of fabric may be connected together by the thread-inserting means. 40 Bags may be sewn in this manner. In Fig. 6, I have shown the manner in which a plurality of threads may be applied to provide an ornamental effect. In Fig. 7, I have shown sets of ornamental threads in groups, varying in number, and in Fig. 8, I have shown another arrangement of grouped threads, all of which may be applied by the means or mechanism forming the subject of my invention.

50 In this connection, of course, it will be understood that a plurality of needles or sets of needles may be set in any desired relation with respect to the toothed members

which effect the crimping or goffering of the fabrics, so as to properly present it to 55 the thread carrying needles.

I claim:

1. Thread-inserting means, comprising a pair of toothed wheels, means for moving said wheels; the latter being adapted to engage and goffer a section of fabric, a needle arranged to enter the goffered folds of the fabric at the bite of said wheels and carry a thread into said fabric, and a toothed chain passing over one of said goffering 65 wheels into engagement with the goffered folds of the fabric and serving as means for piling up the fabric on the needle after such fabric has left its engagement with the wheels. 70

2. Thread-inserting means comprising a pair of toothed wheels, supports for said wheels pivotally connected together; one of said supports being fixed, means for moving said wheels in toothed relation or engagement whereby a section of fabric placed between the same will be given a series of regular folds; one of said wheels being mounted in the fixed support and the other in the movable support hinged thereto, a needle 80 carried by the hinged portion of said movable wheel support; said toothed wheels being grooved to accommodate said needle, means for moving said wheels, and additional means for imparting longitudinal 85 movement to the folded fabric after it has left its engagement with the wheels.

3. Thread-inserting means comprising a pair of toothed wheels, means for moving said wheels in toothed engagement whereby 90 a section of fabric caught between the same will be given a series of crimps or folds, a hinged member supporting one of said wheels and a fixed member supporting the other wheel, a block carried by the hinged 95 portion of said movable supporting member, a needle carried by said block and arranged to receive the folded fabric, means for moving the toothed wheels, and a toothed chain passing over one of said wheels and serving 100 to impart longitudinal movement to the goffered and threaded fabric and pile the same up on said needle.

In witness whereof I have signed this specification.

RUDOLF LOEB.
